UNITED STATES PATENT OFFICE.

EDWARD T. COVELL, OF NEW BEDFORD, MASSACHUSETTS, ASSIGNOR OF
ONE-HALF TO CHARLES F. CUSHING, OF SAME PLACE.

HARNESS-PAD.

SPECIFICATION forming part of Letters Patent No. 357,981, dated February 15, 1887.

Application filed June 26, 1886. Serial No. 206,297. (No model.)

To all whom it may concern:

Be it known that I, EDWARD T. COVELL, a citizen of the United States, residing at New Bedford, in the county of Bristol and State of Massachusetts, have invented certain new and useful Improvements in Harness-Pads; and I do hereby declare that the following is a full, clear, and exact description of the same, reference being had to the annexed drawings, making a part of this specification, and to the letters and figures of reference marked thereon.

Figure 1 of the drawings is a top plan view of my improved harness-pad; Fig. 2, a longitudinal section thereof, and Fig. 3 an under side plan view of the pad.

The present invention has relation to the construction of pads for harness, and the object thereof is to provide a pad which will be both light and durable and will not chafe or gall the animal, and in many respects superior to the pads in ordinary use, which objects I attain by the construction substantially as shown in the drawings, and hereinafter described and claimed.

In the accompanying drawings, *a* represents a covering of leather for the lining *b* of the pad, which lining is composed of a white-metal formed in a thin sheet and having a polished surface. This metal, with its smooth or polished surface, is not in danger of corroding, and will not allow the collection of a heat-holding coating, and serves efficiently as a means for conducting away the heat from the bearings upon the animal. White-metal, therefore, with a polished surface, as a lining

for such class of pads, is especially adapted for the purpose, it having many advantages not found in other metals.

The leather covering *a* and sheet-metal lining *b* are firmly secured together by a binding, *c*, preferably of leather, said binding overlapping the edges of the covering and lining and secured thereto by stitching or in any well-known manner, and the upper side of the pad is provided with a suitable fastening device, *d*, for attaching it to some part of the harness, whereby the pad is held in position on the animal. A harness-pad is thereby provided complete in itself that is both durable and effective and comparatively light, while it can be manufactured and placed in the market at a greatly-reduced cost.

Having now fully described my invention, what I claim as new, and desire to secure by Letters Patent, is—

A harness-pad consisting of a lining of white-metal having a polished surface, a leather covering therefor, and a binding secured around the edges of the lining and covering to hold them together, said pad having a suitable fastening device for securing it in position on the animal, substantially as and for the purpose set forth.

In testimony that I claim the above I have hereunto subscribed my name in the presence of two witnesses.

EDWARD T. COVELL.
